AUTOMOBILE DOOR HANDLE

Charles A. Stebbins, Birmingham, Mich., assignor to General Motors Corporation, Detroit, Mich., a corporation of Delaware

Application August 31, 1954, Serial No. 32,092

Term of patent 7 years

(Cl. D10—8)

Fig. 1 is a front elevational view of an automobile door handle showing my new design;

Fig. 2 is a perspective view of the door handle;

Fig. 3 is an end view of the door handle looking from the left of Fig. 1;

Fig. 4 is a section showing the contour along the line 4—4 of Fig. 1;

Fig. 5 is a section showing the contour along the line 5—5 of Fig. 1; and

Fig. 6 is a section showing the contour along the line 6—6 of Fig. 1.

I claim:

The ornamental design for an automobile door handle, substantially as shown.
